(57) **CLAIM**

The ornamental design for a water pipe assembly for pump training, as shown and described.

DESCRIPTION

FIG. 1 is a front perspective view of a water pipe assembly for pump training, illustrating the new, original, and ornamental design;

FIG. 2 is a first side view of a water pipe assembly for pump training, illustrating the new, original, and ornamental design; FIG. 3 is a second side view of a water pipe assembly for pump training, illustrating the new, original, and ornamental design;

FIG. 4 is a first end view of a water pipe assembly for pump training, illustrating the new, original, and ornamental design; and,

FIG. 5 is a second end view of a water pipe assembly for pump training, illustrating the new, original, and ornamental design. FIG. 6 is a top view of a water pipe assembly for pump training, illustrating the new, original, and ornamental design; and,

FIG. 7 is a bottom view of a water pipe assembly for pump training, illustrating the new, original, and ornamental design. In the drawings, the broken lines depict portions of the design that form no part of the claim.
